UNITED STATES PATENT OFFICE.

CHRISTIAN F. WEIL, OF JEFFERSON TOWNSHIP, WARREN COUNTY, IOWA.

LATCH.

1,359,774.

Specification of Letters Patent. Patented Nov. 23, 1920.

Application filed August 2, 1919. Serial No. 314,896.

To all whom it may concern:

Be it known that I, CHRISTIAN F. WEIL, citizen of the United States of America, and resident of Jefferson township, Warren county, Iowa, have invented a new and useful Latch, of which the following is a specification.

The object of this invention is to provide an improved construction for latches especially adapted for use on screen doors, gates and the like.

My invention consists in the construction, arrangement and combination of elements hereinafter set forth, pointed out in the claims and illustrated by the accompanying drawing, in which—

Figure 1 is an exterior elevation of a screen door to which my improvement is applied. Fig. 2 is a plan of the latch detached from the door, the dotted lines indicating a different location for one of the elements. Fig. 3 is a side elevation of the device mounted on the stile of a screen door, the screen being shown in section, a portion of a door jamb 25 being shown carrying a strike in association with the door and latch. Fig. 4 is an interior elevation showing the latch mounted on a portion of the stile of a screen door and a portion of a door jamb carrying a strike in association therewith, the screen being omitted. Fig. 5 is a vertical section on the indicated line 5—5 of Fig. 4, the door stile and jamb being omitted.

In the construction of the device and its mounting as shown, the numeral 10 designates a base member, preferably made of sheet metal by stamping, pressing or drawing. The flat central or body portion of the member 10 is formed with spaced ears 11 bent around and pivoting on a hinge pin 12 and forming half of a hinge connection to another element, and also is formed with wings 13, 14 standing at right angles to the body and tapering in width toward the lower ends thereof, which wings are formed with upper end portions 15, 15, forming right angles with the line of jointure between the wings and body and adapted to serve as stops at times. Flanges 16, 17 are formed on and extend outwardly from the plane of the wings 13, 14 at oblique angles to the upper ends of said wings and are adapted to serve as stops at times as hereinafter described. The flat body of the member 10 also is formed with a plurality of holes adapted to receive fastening means,

such as screws 18, whereby the entire device may be mounted on a support such as the stile 19 of a door or gate 20. A latching member 21 preferably is made of sheet metal by stamping, pressing or drawing, and the flat body portion thereof is formed at one end with ears 22, alternating with the ears 11 and adapted to be bent around and pivot on the hinge pin 12, thus hinging the latching element to the base element. Hooks 23 and 24 are struck out of the flat body portions of the base member 10 and the latching member 21 respectively and said hooks are connected by a retractile coil spring 25, which spring exerts its force to hold the said members in right-angled relations, the upper ends of the wings 13, 14 contacting with the lower face of the member 21 and resisting the pull of the spring. Wings 26, 27 are formed on and stand at right angles to the side margins of the member 21 and flanges 28, 29 are formed on and extend inwardly from the inner end portions of said wings at oblique angles to the body 21 and opposed to and normally spaced from the flanges 16, 17. It is the function of the flanges 16, 17 on the one hand and the flanges 28, 29 on the other hand to interengage and limit and determine movement of the member 21 on the hinge pin 12 against the pull of the spring 25. Hooks 30, 31 are formed on outer end portions of the wings 26, 27 and said hooks are formed with inclined striking margins 32. Said hooks 30, 31 are shaped and arranged for selective engagement with a strike 33 adapted to be secured to a door jamb 34 and project across the path of travel of one or another of the hooks. A hooked flange 35 is formed on and extends upwardly from the outer end portion of the body 21 and is arranged at right angles to said body, and ears or lugs 36 are struck up from the body into planes parallel with and are spaced from the inner surface of said flange, thus forming a slide seat. A handle 37, preferably formed of bar metal by bending, is provided with a right-angled arm 38 at one end adapted to be mounted or demounted slidingly in the seat provided by the hooked flange 35 and lugs 36. The body of the handle 37 is adapted to extend through an opening in the gate or door, such as a slot 39 in the screen adjacent to the stile 19, and is formed with a roll or loop 40 on its outer end. Downward pressure manually on the roll or loop

40 will oscillate the handle and raise the latching member 21 against the pull of the spring 25, thus moving the hook, immediately employed, away from the strike 33
 5 and permitting the gate or door to be opened. Such gates or doors usually are equipped for gravity or spring closing, and in such event will close automatically and cause the hook to engage, by its striking
 10 margin 32, with and ride over the strike 33 into such position that the hook will engage
 15 the strike and retain the gate or door in closed position. The device is reversible or interchangeably usable on different stiles of the gate or door by changing the handle from one side to the other of the latching member 21, as indicated by dotted lines in Fig. 2.

The strike 33 herein shown and described
 20 is covered in my companion application, Serial Number 314,897 pending concurrently herewith.

I do not desire to be understood as limited to the exact construction shown and described, as the same may be modified in many particulars, within the scope of the appended claims, without departing from my invention.

I claim as my invention—
 30 1. A latch comprising a base member and a latching member hinged together and arranged at angles to each other, a spring connecting said members and resisting rela-

tive movement thereof in one direction, wings on the base member normally engaging the latching member and resisting the pull of the spring thereon, spaced flanges on the wings, other spaced flanges on the latching member, said flanges coacting to limit relative movement of the members against the pull of the spring, means on the latching member for engaging a strike, and means carried by the latching member for releasing the same from the strike.

2. In a latch, a base member and a latching member hinged together, a yielding pressure device acting on said members in one direction, said latching member being formed with a slide seat, and a handle reversibly mounted in the slide seat of said latching member and adapted for manual actuation to move said latching member in opposition to the yielding pressure device.

3. In a latch, a latching member adapted to be hinged to a support, wings formed on said member, said wings being shaped with hooks adapted to engage a strike, and means for oscillating said member.

4. In a latch, a latching member adapted to be hinged to a support, latching means on said member adapted to engage a strike, a slide seat on said member and a handle reversibly mounted in said seat.

Signed at Prole, in the county of Warren and State of Iowa, this 5 day of July, 1919.

CHRISTIAN F. WEIL
